SUPPORT

Peter Thomson, Wilmington, Del.

Application September 22, 1936, Serial No. 101,989

4 Claims. (Cl. 304—5)

This invention relates to the trestles or supports of scaffolds and the like, and more particularly to extensible trestles.

An important object of the invention is to provide a trestle which, while extensible, is very sturdy. Frequently, extensible trestles, adapted to support scaffolding, are not steady and when weight is placed upon the scaffold, the latter rocks and may cause the securing and bracing members 10 of the trestle associated therewith to work loose so that the scaffolding collapses. The novel trestle herein disclosed, retains the scaffold floor boards support timber against movement, even when subjected to heavy weights, and there is no tendency of the securing or bracing members to work loose.

Another important object is to provide an easily set up and knock-down trestle.

Still another object is to provide a device of this kind which may be manufactured at low cost and comprises but few and simple parts.

Yet another object is to provide a trestle for association with scaffolding, the construction of the trestle being such that both longitudinal and transverse swaying of the scaffolding will be prevented.

Other objects and advantages of the invention will be apparent during the course of the following detailed description, taken in connection with the accompanying drawings, forming a part of this specification and in which drawings:—

Figure 1 is a front elevation of the novel trestle.

Figure 2 is an end elevation of the same, secured to a portion of the scaffolding.

Figure 3 is a rear elevation of the novel trestle.

Figure 4 is a fragmentary view, from the rear, of the novel trestle, extended to a greater height. Figures 5 and 6 are sections upon substantially their respective lines of Figure 1.

Figure 7 is a section upon substantially the line 7—7 of Figure 2.

Figure 8 is a section upon substantially the line 8—8 of Figure 3.

Figure 9 is an elevation of the member shown in section in Figure 8.

In the drawings, wherein for the purpose of illustration is shown a preferred embodiment of the invention and wherein similar reference characters designate corresponding parts throughout the several views, the letter A may designate generally the novel trestle or support and the letter B a suitable member forming a portion of the scaffolding.

The trestle or support A preferably includes a pair of main supports or legs 10, which may be of angle iron. When the trestle is set up these supports 10 are disposed so as to converge upwardly, as shown in Figures 1, 3, and 4, but they do not cross one another. The supports 10 are arranged so that an outer angle iron face 11 of each is in substantially a common plane, and the inner angle iron face 12 of the other leg of the angle of each support faces the other. With this arrangement a similar edge 13 of each support faces the other. While the upper extremity 14 of this edge 13 may be beveled, so to provide a cutting edge, it has been discovered that the wall of the angle iron is thin enough so that, when a suitable member B, such as of wood, is placed between the supports, at their upper ends, and these ends are drawn towards each other, the extremities 14 of the edges 13 will bite into the member B.

A horizontally disposed cross piece or member 15 is provided, bridging the supports 10, below and adjacent the upper ends thereof, as shown for example in Figures 1 and 3. This cross piece 15 preferably comprises a flat bar or strip of metal provided with an upper edge 16 which may be serrated or toothed, as shown at 17.

Means for securing this cross piece 15, either pivotally or rigidly, to the supports 10 is provided and may comprise a bolt 20 extending through one support 10 and the cross piece 15 adjacent one end thereof, and a second bolt 21 extending through the other support 10 and the cross piece 15 adjacent the other end thereof. Each bolt is provided with a suitable nut 22. So that there may be some adjustment of the length of the cross piece 17 between the two supports 10, one or more extra perforations 23 may be provided extending through the cross piece 15, so as to accommodate the shank of the bolt 21. When the nuts 22 are not tightened upon their respective bolts, there is a pivotal connection between the support 10 and the cross piece 15, but when the nuts are well tightened, there is a rigid connection.

Means for spreading and bracing the supports 10 is provided and preferably comprises a lever 25 which may be a suitable length of metal bar, pivoted at one end 26 to one support 10, as by a bolt 27 extending through the lever 25 and support wall and, preferably, having a squared head 28 countersunk below the inner face of the wall of the support 10, as shown in Figure 5. Pivotally connected to the lever 25 and the other support 10, is a link 29. As is well known in the construction of leverage devices of this kind, the link 29

29 is pivotally connected to the lever 25 as shown in Figures 1 and 3. Preferably a suitable bolt 30 extends through the lever 25, intermediate its ends, and through one end of the link 29, while another bolt 31 pivotally connects the other end of the link 29 to the second support 10, as shown particularly in Figure 5. Each of the bolts 27, 30, and 31 may be provided with suitable nuts 32, and a suitable spaced collar 33 may be disposed upon the shank of the bolt 31, between the link 29 and support 10, as shown in Figure 5, in order to space the link from the support 10 a sufficient distance so that the lever may be forced down between the two and come to rest upon the periphery of the collar 33. It is apparent that, as the lever is pushed or drawn downwardly, the supports 10 will spread apart at their lower ends and move towards each other at their upper ends until the lever comes to rest as heretofore described. On the other hand, as the lever 25 is drawn upwardly, the supports 10 will be drawn towards each other at their lower ends and will spread apart at their upper ends.

Slidable along the inner faces of the angle iron supports 10 are auxiliary supports 35, which may be angle iron of less width and length than the supports 10, as shown particularly in Figures 3, 5, and 8.

So that these auxiliary supports 35 may be employed, in order to lengthen the trestle A, and be held in place, a securing means is provided and preferably consists of a suitable section of material, such as a short, flat strip 36 of metal which extends from one edge 13 to the other edge of each support 10, as shown in Figure 8, and may be welded thereto. At least two of such strips 36 are secured to each support 10, and spaced apart adjacent the lower end of the support. Each strip 36 may be provided with a suitable screw threaded perforation 37, midway its ends, through which extends a thumb screw 38, or the like, having a beveled free end so that it may engage and bear against the inner faces of the auxiliary angle iron supports 35 at the juncture 45 of the two walls forming each auxiliary support.

Preferably, pivotally carried by each support 10, is one of a pair of arms 40 which may be of resilient metal. These are pivoted to the supports 10, as shown particularly in Figures 1, 2, 50 and 7, by bolts 41 extending through suitable perforations in the arms 40 and supports 10, the heads 42 of these bolts being countersunk. Suitable nuts 43 are provided for the bolts 41. For the greater portion of their length, these arms 55 converge but do not meet. At their free ends 44, they are provided with suitable sharpened projections or teeth 45, which are disposed to point towards each other, since the free ends 44 of the arms 40 parallel each other, as shown particularly in Figures 1, 3, and 7. The arms 40 are joined together by a rod 46 extending through them, having a head 47 at one end, screw threads 48 at the other end, and a nut, such as a wing nut 49, to cooperate with these screw threads 47 to 65 draw the two ends 44 of the arms towards each other when the wing nut 48 bears against one of the arms and the head 47 of the rod 46 bears against the other arm. When the wing nut 48 is unscrewed, the arms, due to their resiliency, will 70 move away from each other.

It is apparent that, with these bolt and nut connections, the trestle A may be disassembled in order to form a compact bundle for shipping and storage, yet the trestle may be quickly and easily 75 set up again.

With the trestle A set up as shown in Figure 1, and the nuts 22 loosened so that the shanks of the bolts 20 and 21 provide pivots for the supports 10 and cross piece 15, and the lever 25 swung upwardly, a suitable member B, such as a plank 50, may be dropped into place upon the toothed edge of the cross piece 15. By now bearing down upon the lever 25, the supports 10 will move towards each other at their upper ends and the edges 14 will bite into the opposite faces 51 of the plank 50, and at the same time, due to the arc described by these edges 14, the plank will be forced down upon the teeth 17 of the cross piece 15. The nuts 22 may now be tightened upon their respective bolts 20 and 21, so that there is a rigid connection between the supports 10 and cross piece 15.

By swinging the arms 40 upwardly so that a portion of the free ends 44 are to either side of the plank 50 and face the opposite faces 51 thereof, the free ends may be struck by a suitable tool so as to force the teeth 45 into the plank 50, and the free ends may be secured in contact with the plank by tightening up on the wing nut 48 upon the screw threaded end of the rod 46.

It is apparent that the bolt 21 may be inserted into the perforation 23 of the cross piece 15 in order to lengthen the distance between the two supports 10 at the cross piece 15, so as to accommodate planks of different thicknesses and regulate the extent the edges 14 will bite into the plank.

In order to lengthen the trestle A, the thumb screws 38 may be loosened so that the auxiliary supports 35 may be slidably extended from the lower end of the main supports 10, whereupon the screw threads 38 may be again tightened when the extended trestle has reached its proper height.

Even when exceptionally heavy weight or high pile of material are placed upon the scaffold platform supported by the member B, there will be no dangerous side or longitudinal sway of the scaffold and, as a consequence, the various bolted connections will not work loose, nor will other types of screw threaded and similar connections work loose. This absence of side and longitudinal sway is due to the method of providing a biting contact with the sides and bottom of member B and the bracing effect of the arms 40. A mere contact of supports or cross pieces with the member B will not obviate dangerous side and longitudinal sway and it is also important that, the pivotal connection provided by the bolts 20 and 21 between the supports 10 and the cross piece 15 be changed to a rigid connection by tightening upon the bolts 22 or when the trestle has been finally adjusted, as has been described.

Various changes may be made to the form of invention herein shown and described, without departing from the spirit of the invention or the scope of the claims.

What is claimed is:

1. In an adjustable trestle, a pair of supports converging upwardly, a cross piece bridging said supports below and adjacent the upper ends thereof and having a serrated upper edge, means for selectively securing said cross piece rigidly and pivotally to said supports, and means for spreading and bracing said supports, disposed below said cross piece, whereby when a suitable member is placed upon said cross piece and said supports are spread apart at their lower ends and are drawn towards each other at their upper ends, by said last named means, said member

will be forced down upon said serrated edges by said upper ends coming into contact with said member.

2. In an adjustable trestle, a pair of supports converging upwardly and each provided with a biting edge at its upper end, a cross piece bridging said supports below and adjacent said biting edges, said cross piece having a toothed upper edge, means for selectively securing said cross piece rigidly and pivotally to said supports, and means for spreading and bracing said supports, disposed below said cross piece, whereby, when a suitable member is placed upon said cross piece and said supports are spread apart at their lower ends by said last named means, said biting edges will enter said member and said member will be forced down upon said toothed edge and retain said member rigidly upon said cross piece.
3. In an adjustable trestle, a pair of supports converging upwardly, each of said supports comprising an angle iron with an edge of one support facing a like edge of the other support, a cross piece bridging said supports adjacent their upper ends, said cross piece having a serrated upper edge, means for selectively securing said

cross piece rigidly and pivotally to said supports, and means for swinging said supports upon their pivotal connections with said cross piece, including a lever disposed below said cross piece and operatively connected with said supports, whereby when said lever is in one position said edges of said angle irons will move towards each other and toward said serrated edge of said cross pieces at the upper ends of said supports so that a suitable member disposed upon said serrated edge will be forced by said edges, at the upper ends of said supports, downwardly upon said serrated edge.

4. In a scaffolding trestle, a pair of upwardly converging supports, means connecting said supports adjacent their upper ends, a pair of arms of resilient material secured to said supports and extending upwardly and away therefrom, said arms converging towards one another and each being provided with a tooth at its free end, said teeth pointing towards one another, and means for moving the free ends of said arms and said teeth towards one another.

PETER THOMSON.
